CLAIM

The ornamental design for a support cabinet for key cutting equipment, as shown and described.

DESCRIPTION

FIG. 1 is a front perspective view of a support cabinet for key cutting equipment showing my new design;

FIG. 2 is a front elevational view thereof;

FIG. 3 is a top plan view thereof;

FIG. 4 is a side elevational view thereof taken from the left of FIG. 2, the right side elevational view being the mirror image thereof;

FIG. 5 is a rear elevational view thereof; and

FIG. 6 is a bottom plan view thereof.
